UNITED STATES PATENT OFFICE.

JOHN W. DYER, OF MOUNT AIRY, NORTH CAROLINA, ASSIGNOR OF ONE-HALF TO JOHN B. NUTT, OF SAME PLACE.

CAR-COUPING.

SPECIFICATION forming part of Letters Patent No. 499,016, dated June 6, 1893.

Application filed March 25, 1893. Serial No. 467,629. (No model.)

To all whom it may concern:

Be it known that I, JOHN W. DYER, a citizen of the United States, and a resident of Mount Airy, in the county of Surry and State 5 of North Carolina, have invented certain new and useful Improvements in a Combined Buffer and Car-Coupling; and I do hereby declare that the following is a full, clear, and exact description of the invention, which will 10 enable others skilled in the art to which it appertains to make and use the same, reference being had to the accompanying drawings, which form a part of this specification, and in which—

15 Figure 1 is a perspective view of my combined buffer and automatic coupling. Fig. 2 is a perspective view of the coupling knuckle, removed from the drawhead. Fig. 3 is a longitudinal sectional view on a horizontal plane 20 through the drawbar and drawhead, showing my peculiarly constructed spring-latch or locking device, and also the flat buffer-spring. Fig. 4 is a transverse sectional view on line $x-x$; and Fig. 5 is a perspective detail view 25 of the buffer-spring, removed from its recess in the drawbar.

Like letters of reference denote corresponding parts in all the figures.

This invention relates to automatic car 30 couplers of the type known technically as "knuckle couplings," and it consists in the novel construction and combination of parts of a coupling of that class whereby the drawhead will operate in the two-fold capacity of 35 coupler and buffer, thus obviating and dispensing with the use of separate buffers and buffer-springs, as will be hereinafter more fully described and particularly pointed out in the claim.

40 Referring to the drawings, the letter A denotes the drawbar and B the drawhead of my improved automatic car coupling. The former is slotted longitudinally so as to form a rectangular recess or chamber, C, open on both 45 sides but closed at the top and bottom and at both ends, within which is inserted a flat serpentine spring, D, the rear end of which abuts upon a cross bar E, inserted transversely through the rear end of chamber C and held 50 in place between pins, e e, fastened in the carrier iron, or some other suitable rigid part of

the frame. The forward end of spring D bears against the solid fore-end of the recessed drawbar, just back of the drawhead B. Said drawhead is recessed at f, as usual, to 55 make room for the pivoted knuckle F, which swings upon a stout fulcrum-pin or pintle G. The knuckle F is recessed at H to admit of the insertion of an ordinary link when the drawhead is to be used with an ordinary pin- 60 and-link coupling, in which case the coupling pin is inserted through registering holes h h in the forward bifurcated end of the knuckle. The inner end of this, which projects into the recess f, is elongated to form a tail piece F', 65 which is notched or bifurcated at its outer end, as shown at i; the said notched end being curved or concave on one side, as shown at i, for the purposes hereinafter set forth.

Just back of the recess f, within which the 70 inner end of the tail piece F' plays, is a box J, forming a chamber or recess for the spring-latch K, which interlocks with the recess I. This latch consists of a sliding bolt, beveled at its forward end, and having a shank, k, 75 which is encircled by a coiled spring L, operating to push the latch into its locked position. At the projecting rear end of the latch stem k, which projects out through an aperture in the rear end of box J, is a ring, j, for 80 the attachment of a chain, M, by means of which the latch may be drawn back and disengaged from the forked tail piece F' of the coupling knuckle when it is desired to uncouple the cars. The chain M is connected, 85 for this purpose, to any of the well-known (and therefore not shown) systems of rods and levers whereby the uncoupling may be effected from the platform of the car, on passenger coaches, or from the roof or sides of 90 the car, as in the case of box cars and freight cars equipped with my improved automatic coupling.

From the foregoing description, taken in connection with the drawings, the operation 95 of this combined coupling and buffer will readily be understood. When cars are to be coupled, the latch K is withdrawn and the knuckle F is turned in the position shown in dotted lines in Fig. 3. As the cars come together, the drawheads will interlock in the well understood manner peculiar to this type 100

of couplings, the knuckle at the same time interlocking at its bifurcated or notched inner end with the spring-actuated locking-latch K, so that the interlocking or coupled drawheads of connecting cars cannot possibly become uncoupled until the latch is again withdrawn and the knuckle released, which operation may be performed, as I have already stated, from the platform, roof, or sides 5 of the car, and without the necessity of going in between the cars. It will further be observed that the flat spring D, which is placed within the longitudinally slotted drawbar, operates as a buffer spring to cushion the blow 10 on the drawhead when the cars come together. In addition to this buffer spring, the drawbar is or may be equipped with the usual tension 15 spring encircling it, but which, as it forms no part of my improvement, I have not shown 20 on the drawings.

I have referred to the rounded or concave side of the bifurcated tail-piece F' of the knuckle, as shown at i, on one side of the latch recess I. This is for the purpose of 25 guiding the inner end of an ordinary link (when the drawhead is to be used with an ordinary pin-and-link coupling) into the recess of the drawhead as the cars come together in coupling with such a link. In that case, the 30 inner end of the link, striking against the concave side i of the notched tail-piece F', will throw this to the left or against the bevel of the latch and thereby cause the knuckle to interlock automatically with the spring 35 latch, the same as when two knuckle-couplings are used together.

It will be obvious that the detailed shape of the "knuckle" may be modified to conform

to the shape of other couplings of the same type, as, for example, the "Janney" coupler, "Miller" coupler, "Thurmond" coupler, and many other so-called "knuckle" couplings which are now in use on various roads, without departing from the spirit of my invention; and that the size and configuration of the several operative parts of my improved 40 automatic coupling may be changed or adjusted in matters of detail to make it adapted for practical use with other automatic or non-automatic couplers now employed to a 45 greater or less extent, or which may come into use at some future time, without changing the general construction and combination of parts which form the subject-matter of my improvement.

Having thus described my invention, I claim and desire to secure by Letters Patent of the United States—

In a car coupling of the described type, the combination of the slotted drawbar, the flat spring placed within the recess in the same and arranged and operating as described, the recessed knuckle drawhead, the pivoted coupling knuckle having a rearwardly extending bifurcated tail-piece, and the bevelled spring-latch working in a horizontal plane; substantially as and for the purpose herein shown and set forth.

In testimony that I claim the foregoing as my own I have hereunto affixed my signature in presence of two witnesses.

JOHN W. DYER.
